Primary Examiner — Darlington Ly

(57) **CLAIM**

The ornamental design for an electric bicycle, as shown and described.

DESCRIPTION

FIG. 1 is a left side elevation of an electric bicycle embodying my new design;

FIG. 2 is a right side elevation view thereof;

FIG. 3 is a front elevation view thereof;

FIG. 4 is a rear elevation view thereof;

FIG. 5 is a front and left side perspective view thereof;

FIG. 6 is a rear and right side perspective view thereof; and

FIG. 7 is an enlarged and partial perspective view of portion

7 shown in FIG. 6; and,

FIG. 8 is an enlarged and partial perspective view of portion

8 shown in FIG. 6.

The broken lines illustrate portions of the Electric two-wheeler that do not form part of the claimed design.

1 Claim, 8 Drawing Sheets
